UNITED STATES PATENT OFFICE.

JOHN ARTHUR KAYE, OF SAULT STE. MARIE, ONTARIO, CANADA.

BOTTLE-CAP.

1,341,177.

Specification of Letters Patent. Patented May 25, 1920.

Application filed March 6, 1919. Serial No. 280,914.

To all whom it may concern:

Be it known that I, JOHN ARTHUR KAYE, a subject of the King of Great Britain, residing at Sault Ste. Marie, Province of Ontario, Dominion of Canada, have invented a new and useful Bottle-Cap; and I do hereby declare the following to be a full, clear, and exact description of the invention, such as will enable others skilled in the art 10 to which it appertains to make and use the same.

The present invention relates to a bottle cap, and has for its object to provide a device of this character which embodies novel 15 features of construction whereby it can be used repeatedly and can be placed in position or removed therefrom without the use of any special tools.

Further objects of the invention are to 20 provide a device of this character which is comparatively simple and inexpensive in its construction, which will tightly seal the mouth of the bottle when in position thereon, which is not liable to become accidentally 25 removed in handling the bottle, and which can be easily manipulated with the hands.

With these and other objects in view, the 30 invention consists in certain novel combinations and arrangements of the parts as will more fully appear as the description proceeds, the novel features thereof being 35 pointed out in the appended claim.

For a full understanding of the invention, reference is to be had to the following description and accompanying drawings, in 40 which:—

Figure 1 is a side elevation of a bottle neck which is provided with a cap constructed in accordance with the invention.

Fig. 2 is a horizontal sectional view 45 through the cap, taken on the line 2—2 of Fig. 3.

Fig. 3 is a vertical sectional view taken on the line 3—3 of Fig. 2.

Fig. 4 is a view similar to Fig. 3, showing the cap as clamped in position on the bottle neck.

Fig. 5 is a detail sectional view of the locking ring.

Fig. 6 is a transverse sectional view similar to Fig. 2, showing the locking ring as held in operative position by means of the 50 detent.

Corresponding and like parts are referred to in the following description and 55

indicated in all the views of the drawings by the same reference characters.

Referring to the drawings, which illustrate one embodiment of the invention, the numeral 1 designates the neck of a bottle which is provided at a point adjacent the end thereof with an exterior annular rib 2, said rib being utilized in securing the cap in position upon the bottle. The cap 3 is 60 formed of sheet metal and has side flanges 4 of a suitable length to extend downwardly along the sides of the bottle neck and reach beyond the rib 2. The cap is preferably 65 formed of spring metal so that it will spring back into shape after being bent, and the top of the cap is lined with a pad 5 of cork or similar compressible material which engages the upper end of the bottle neck to seal the same when the cap is clamped in position thereon. 75

The depending side flange 4 of the cap is provided at intervals with a series of outwardly projecting cam lugs 6, said lugs being shown as stamped outwardly from the material of which the cap is formed. A 80 clamping ring 7 is rotatably mounted upon the flange 4 of the cap, being formed with cam grooves 8 which receive the lugs 6. The cam grooves 8 each have a deep end and a shallow end, and the outer ends of the lugs 85 6 are rounded so as to slidably engage the cam walls of the grooves. When the locking ring 7 is rotated to bring the lugs 6 into the deep ends of the grooves 8, the flange 4 of the cap assumes a substantially cylindrical 90 shape, as indicated by Fig. 3, so that it can be fitted upon the bottle neck or removed therefrom. After the cap has been applied to the bottle neck, the locking ring 7 is rotated to bring the lugs 6 into the shallow 95 ends of the cam grooves 8, thereby forcing the lugs and corresponding portions of the side flange 4 of the cap inwardly and drawing the flange into a locking engagement with the rib 2 of the bottle neck, as indicated by Fig. 4. The bottle cap is then 100 locked in position upon the bottle neck, and the cork lining 5 drawn into a firm engagement with the bottle neck so as to effectively seal the same. As shown on the drawing, 105 the deep ends of the cam grooves 8 in the locking ring communicate with openings 9 extending downwardly through the lower edge of the locking ring, said openings being of a sufficient size to receive the lugs 6 110

so that the cap and ring can be assembled or taken apart when the ring is brought into position with the lugs of the cap opposite the openings 9.

- 5 If desired, a detent 10 may be provided for locking the ring 7 in operative position. Said detent may be formed of spring material and seated in a recess 11 in the periphery of the locking ring, one end of the 10 detent being riveted or otherwise secured at 12 to the ring, while the other end thereof is formed with a nose 13 which extends through an opening in the ring and is adapted to engage a notch 14 in one of the lugs 6.
- 15 When the locking ring is rotated into operative position the nose 13 will automatically seat itself in the notch 14 and thereby prevent backward or reverse movement of the locking ring. Accidental disengagement of 20 the cap from the bottle will thus be rendered an impossibility, although when it is desired to remove the cap it is merely necessary to spring the free end of the detent 10 outwardly and disengage the nose 13 thereof from the notch 14, preparatory to rotating the ring and releasing the cap.
- 25 Having thus described the invention, what

I claim as new and desire to secure by Letters Patent, is:—

A bottle cap including a sheet metal body 30 formed with a flexible peripheral flange, a series of rounded lugs projecting laterally from the flange at a point adjacent the free edge thereof, one of the said lugs having a notch therein, a locking ring rotatably mounted 35 upon the flange and formed with cam grooves which receive the lugs and coöperate with the rounded ends thereof to flex the flange of the cap body inwardly when the locking ring is rotated, and a spring detent mounted upon the locking ring and formed with a nose extending through the locking ring and adapted to engage the before mentioned notch of one of the lugs to hold the ring against backward rotation 45 after it has been manipulated to lock the cap in position.

In testimony whereof I have signed my name to this specification in the presence of two subscribing witnesses.

JOHN ARTHUR KAYE.
